UNITED STATES PATENT OFFICE

102,100

DESIGN FOR A STORE

William Donald White, Algona, Iowa

Application July 14, 1936, Serial No. 63,841

Term of patent 7 years

To all whom it may concern:

Be it known that I, William Donald White, a citizen of the United States, residing at Algona, in the county of Kossuth and State of Iowa, have invented a new, original, and ornamental Design for a Store, of which the following is a specification, reference being had to the accompanying drawings, forming a part hereof.

I claim:

The ornamental design for a store, as shown and described.

WILLIAM DONALD WHITE.
